UNITED STATES PATENT OFFICE

HERBERT J. HAWTHORNE, OF CONROE, TEXAS

DETACHABLE BLADE DRAG BIT

Application filed March 11, 1933. Serial No. 660,411.

My invention relates to well drills for use in drilling deep wells for oil, gas, sulphur and the like, and pertains more particularly to bits of the scraping type in which the material at the bottom of the hole is removed through a scraping or cutting blade.

It is an object of the invention to provide a bit having a detachable blade thereon which may be mounted or removed from the head of the bit conveniently and expeditiously.

It is another object to provide a bit head having a detachable blade thereon, and in which the flushing fluid may be distributed against the cutting end of the bit without leakage or wear about the upper end of the blade.

I contemplate the provision in the head of the bit of a packing means about the joint between the head and the blade whereby a tight seal may be easily formed which will prevent the loss of flushing fluid around the joint and consequent wear at that point.

It is a further object to so form the blade and the socket in the head into which the blade is fitted, that a firm and rigid connection may be formed between the blade and the head so as to avoid any relative movement in use.

The invention resides in the particular construction and arrangement of the parts making up the bit, a full disclosure of which will be made in the specification which follows:

With reference to the drawings herewith, Fig. 1 is a front view partly in central, vertical section illustrating one form of my invention.

Fig. 2 is a side view of the bit shown in Fig. 1 partly in elevation and partly in central, longitudinal section.

Fig. 3 is a transverse section on the plane 3-3 of Fig. 1.

Fig. 4 is a central transverse section on the plane 4-4 of Fig. 1.

Fig. 5 is a broken section taken approximately on the plane 4-4 of Fig. 1 and illustrating a slightly different form of through bolt employed in securing the parts together.

Fig. 6 is a top plan view of a four-way blade removed from the bit head.

Fig. 7 is a front elevation of the blade shown in Fig. 6.

Fig. 8 is a side elevation of the blade shown in Fig. 7, the broken lower end of the bit head being shown in section.

Fig. 9 is a broken, vertical section of the connecting device shown in Fig. 5.

In forming my bit I employ a bit head 1 having a tapered upper shank 2 threaded for engagement with the drill collar, or coupling. The head 1 is approximately cylindrical in shape at its upper end, and the body portion 3 of the bit head is widened out in the plane of the blade of the bit and is approximately oval in cross-section, as shown in Fig. 3. The lower end of the body is rounded somewhat and provided with a transverse slot therein to receive the blade of the bit. This slot is formed centrally with a socket 4 which is tapered upwardly into the head and terminates in a shoulder 5 against which a packing ring or gasket 6 of compressible packing may be placed. There is a longitudinal passage 7 through the head of the bit terminating in the socket 4. As will be seen in Fig. 1, the slot 8 at each side of the socket is also tapered upwardly to receive the blade 9 of the bit.

The blade 9 may be a so-called two-way or four-way blade. In Figs. 1 to 4, inclusive, a so-called two-way blade is shown. This blade is formed like the usual fish-tail bit at its lower end, having cutting edges 10 at the lower end, the blade being divided midway of its sides and curved forwardly in the direction of rotation of the bit, one edge being curved in a direction opposite to that of the other. Midway of the sides of the blade and spaced upwardly from the lower end is a head 11 which is rounded at 12 adjacent the lower end and is tapered upwardly to fit within the socket 4 in the head of the bit. At its upper end it is provided with a shoulder 13 to abut against the packing ring 6. There is a socket 14 formed in the head 11 of the bit corresponding with the size of the passage through the body of the bit head.

This passage of recess in the head terminates short of the lower end 12 on the blade, and is provided with outwardly inclined fluid passages 15, one on each side of the head, discharging on to the forward face of the cutting blade.

I provide a removable water pipe 16 through the head of the bit and projecting somewhat into the head of the blade 9. It 10 overlaps the packing gasket 6 and forms a seal therewith when the blade is drawn firmly into the head. This construction will be understood from Fig. 1. While this water pipe 16 is made removable it is to be understood 15 that it may be formed integrally with the head if desired.

The blade is secured within the body of the bit by through bolts 17, one on each side of the body and extending through the 20 slotted openings 18 in the blade. These through bolts may be of ordinary character having a nut 19 on one end thereof whereby the bolt may be tightened rigidly.

While I have shown an ordinary through 25 bolt employed for this purpose, I also contemplate a through bolt such as is shown in Figs. 5 and 9. In this arrangement I use a key or bushing 20 which may engage through a tapered opening 18' in the body 30 and the blade. The said opening 18', as shown in Fig. 9, is elongated so that when the key or bushing 20 is engaged therein it will have a wedging contact with the upper wall of the slotted opening 18', and as the 35 key is drawn into position by a bolt or screw 21, the blade will be forced upwardly into the tapered slot 8 in the head.

In Fig. 5 I have shown the key as being 40 formed with a threaded socket to receive the cap screw 21, and it will be noted that when the said screw is tightened into the socket in the key, the key will be drawn tightly 45 into position. In Fig. 9, an ordinary slotted screw head is formed on the bolt so that a screw-driver may be employed in tightening the key.

In Figs. 6, 7, and 8 I have shown a so-called four-way bit. The blade 9' is similar 50 in general shape to that shown in the first embodiment. However, in this modification, the blade 9' is approximately shorter and extends but a short distance below the lower curved end 12 of the head of the blade. 55 There is also formed a second blade 23 at right angles to the blade 9 and terminating at 24 shortly above the lower end of the blade 9. Said blade 23 projects forwardly 60 beyond the blade 9' and has the usual cutting edge 25 commonly used on fishtail bits. The channels for the flushing fluid are formed at 26 and 27 to discharge the fluid 65 toward the cutting edges of the blades 9' and 23. It is to be understood that the four-way blade is secured in the body of the bit

in the same way as was noted relative to the first described blade.

It will be noted that when the blade is assembled in the body of the bit, as shown in Figs. 1 and 2, the assembled device will be of general oval shape except for the lower cutting edge which is adapted to be washed effectively by the flushing fluid. This shape of the head and blade allows the device to be easily cleared of material tending to adhere thereto and this bit will hence be difficult to ball up with mud, as is usually the case with fish tail bits. Furthermore, if it is necessary to spud with this bit, any material thereon may be easily loosened. Furthermore, this structure is easy to assemble, in that the blade of the bit may be easily fitted within the lower end of the head and then tightened into position by means of the through bolts. When thus tightened, the upper end of the blade engages firmly with the packing gasket 6 so that no leakage can occur out of the channel 7 for the flushing fluid. This avoids any tendency for wear at this point, and materially lengthens the life of the tool. Due, also, to the shape of the blade, and the socket in which it engages, a tight wedging fit is obtained which avoids loosening of the blade in the body of the bit. However, if the blade tends to become loosened, it may be easily tightened by means of the bolts or screws 21.

The further advantages of this tool will be obvious to those skilled in the art.

Having described my invention, what I claim is:

1. A bit of the character described comprising a bit body, a detachable blade having its upper end tapered, a head axially of said blade tapered upwardly to a shoulder, a socket in said body to receive said head, slots on each side of said socket shaped to form a wedging fit with said blade, said head and bit body being constructed with registering openings forming a passage for flushing fluid axially thereof, said head having channels leading to the lower cutting edge of said blade, and means to form a seal between said shoulder and said body about said passage.

2. A bit of the character described comprising a bit body, a detachable blade having its upper end tapered, a head axially of said blade tapered upwardly to a shoulder, a socket in said body to receive said head, slots on each side of said socket shaped to form a wedging fit with said blade, said head and bit body being constructed with registering openings forming a passage for flushing fluid axially thereof, said head having channels leading to the lower cutting edge of said blade, a removable pipe in said body overlapping said shoulder and packing means in said body adapted to be engaged by said shoulder.

3. A bit of the character described comprising a body approximately oval in transverse cross section, a tapered threaded shank thereon, an upwardly tapered slotted recess 5 in the lower end of said head, a fish tail blade fitting in said recess, means to wedge said blade firmly into said tapered recess, and secure it therein, a fluid channel in said body and said blade, and means to form a 10 seal about said channel at the upper end of said blade.

4. A bit of the character described comprising a body approximately oval in transverse cross section, a tapered threaded shank 15 thereon, an upwardly tapered slotted recess in the lower end of said head, a fish tail blade fitting in said recess, the upper end of said blade being tapered in thickness and beveled upward from its side edges, means 20 to wedge said blade firmly into said tapered recess, and secure it therein, a fluid channel in said body and said blade, and means to form a seal about said channel at the upper end of said blade.

25 5. A drill bit having a body, a tapered shank thereon, an upwardly tapered central

socket in the lower end of said body, slots communicating with said socket, a blade having a head tapered to fit within said socket, a channel for flushing fluid axially through said body and said head to a point short of the lower end of said head, outlets 70 from said channel, means on said body extending into the channel in said blade, means to seal about said channel at the upper end of said blade, and means to secure said blade 75 in said body.

6. A drill bit having a body, a tapered shank thereon, an upwardly tapered central socket in the lower end of said body, slots 80 communicating with said socket, a blade having a head tapered to fit within said socket, a channel for flushing fluid axially through said body and said head to a point short of the lower end of said head, outlets 85 from said channel, longitudinally extending slotted openings in said blade, keys fitting transversely through said head and through 90 said openings, and screws to tighten said keys and draw said blade firmly into said body.
